H. TSCHERNING

MOP

Filed Dec. 15, 1926

Inventor,
Henry Tscherning,
By Dyerforth, Lee, Crittenton, Miles,
Attys.

UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

MOP.

Application filed December 15, 1926. Serial No. 154,918.

My invention relates, more particularly, to mops of the type comprising a handle portion carrying at one end a head connected therewith and forming a stationary jaw 5 and involving a bail-like movable jaw cooperating with the stationary jaw and between which the swab is rigidly held, one of the objects of my invention being to provide a novel, simple and inexpensive construction of stationary jaw.

My invention also relates, as to another phase thereof, to a mop of the type above described and in which the movable jaw cooperates with a spring which surrounds the handle and is engaged by a device which, when moved to one position, opens the jaws and when actuated to another position forces the movable jaw towards the fixed jaw by a yielding action, whereby the jaws accommodate themselves to swabs of different thicknesses and firmly clamp the same therebetween. In this connection it may be stated that the springs referred to, as mops of the general character above stated have hitherto been provided, are of the coil type, it being the intention, in the manufacture of the mops, to hold the outer end of the coil spring in fixed relation to the head forming the stationary jaw, the opposite free end of the spring being engaged by the device through the medium of which the bail-like movable jaw is actuated to different positions relative to the stationary jaw as stated, it being another object of my invention to provide novel and simple means for preventing the coil spring from rotating on the handle portion out of engagement with the fastening means at its outer end to prevent detrimental disarrangement of the parts of the construction.

Referring to the accompanying drawing:

Figure 1 is a view in front elevation of a mop constructed in accordance with my invention, a portion of the handle being cut away and the swab omitted. Fig. 2 is an edge view of the construction shown in Fig. 1. Fig. 3 is an enlarged view in longitudinal sectional elevation of the device shown in Fig. 1 with the handle portion shown in elevation. Fig. 4 is a face view of the blank from which the stationary jaw of the mop is formed; and Fig. 5, a sectional view taken at the line 5 on Fig. 1 and viewed in the direction of the arrow.

In the construction shown the handle, or

bar, portion of the mop represented at 6 and which is commonly made of wood, is provided at its outer end with a head 7 shown as formed of sheet metal and comprising the stationary one of the swab-holding jaws of the device, this jaw member being formed from a single sheet of metal as hereinafter described and presenting a socket portion formed of the oppositely bent strap portions 8 and 9 at which the head fits over the outer end of the handle 6. The head 7 is held on the handle 6 by means of a staple 10 which passes at one of its prongs through an opening 11 in the lower strap portion 9 of the head and extends at both of its prongs into the handle portion 6.

The movable bail-like jaw of the mop is represented at 12 and cooperates with the stationary jaw as in constructions as hitherto provided, the rear arms of the bail, these arms being represented at 13, being connected with a plate-like member 14 which opposes a side of the handle 6 and is transversely curved presenting rearwardly extending ears 15 to which the arms 13 are pivotally connected, the forward end of the plate-like member 14 being formed with a loop 16. The construction also involves a coil spring 17 which surrounds the handle portion 6 and is compressible in a direction lengthwise of the latter. The upper end of the spring 17 abuts the underside of the head 7 and is held in position by means of the staple 10 through which the free upper end 18 of the spring 17 extends. The lower end of the spring 17 passes loosely through the loop 16 of the plate 14.

In accordance with one phase of my invention the stationary jaw-forming head 7 is formed from a single sheet of metal preferably of the shape shown in Fig. 4 to provide the relatively deep notches 19 at opposite edges thereof, and the shallow notches 20 in these edges, the metal being slit along the lines 21 and 22. In forming the head from the blank of Fig. 4, the metal between the slits 21 and 22 is bent to provide the strap portion 8 and the metal at the opposite sides thereof deflected in the opposite direction to provide the strap portions 9 which together form the socket portion referred to. The metal at the outer portion of the blank is bent upon itself along the dotted line 23 to present the flatwise opposing portions 24 and 25 and upon the dotted line 110

26 to present the section 27 which extends at an oblique angle to the section 24, the blank being also bent along the dotted line 28 to cause the sections 24 and 27 to extend 5 at substantially the same angle to the axis of the head as shown in Figs. 2 and 3 thereby providing a trough or groove 29 adapted to receive the cross-piece 30 of the bail-like jaw 12, the side arms of which latter extend into, 10 and are guided by, the notches 19 provided in this jaw at the ends thereof, it being understood that the swab (not shown) with which the structure shown and described is to be equipped, would extend into the trough 15 29 and be overlapped by the bail 12 which operates to firmly hold the swab in position for use when the parts occupy the position shown in the drawing in which the spring 17 is under compression.

20 According to the other phase of my invention the rear end of the spring 17, at the convolution thereof which extends through the loop 16, is deflected, as represented at 31, to form a shoulder cooperating with the end 25 of the loop and preventing the spring 17 from rotating out of engagement with the staple 10, it being preferred that the forward end of the spring and represented at 32 extends substantially in contact with the 30 jaw 7 and the rear end of the spring and represented at 33 extends closely adjacent to the side edge of the plate member 14 when the parts are in the position shown. The spring at both sides of the loop 16 is shown

as deflected whereby, in addition to the shoulder 31 at one end of the loop, another shoulder 34 is provided adjacent the other end of this loop. This last referred to shoulder is not essential for the holding of the spring against rotation, but is produced as 40 an incident to the operation of forming the shoulder 31.

While I have illustrated and described a particular construction embodying my invention, I do not wish to be understood as 45 intending to limit it thereto as the same may be variously modified and altered without departing from the spirit of my invention.

What I claim as new and desire to secure by Letters Patent is:

50 A mop comprising, in combination, a handle, a jaw on said handle, a second jaw movable relative to said first-referred-to jaw, a coil spring surrounding said handle and compressible lengthwise thereof to force said movable jaw toward said first-named jaw to clamp and retain a swab therebetween, a device engaging one end of said spring for controlling said movable jaw and through 55 which a convolution of said spring extends and formed of a flat loop overlying said handle, and holding means at the other end of said spring, said spring having a substantially straight portion extending through 60 said loop and cooperating therewith to prevent rotation of said spring out of engagement with said holding means.

65 HENRY TSCHERNING.
